UNITED STATES PATENT OFFICE.

JOHN R. MORRISON, OF GLENS FALLS, NEW YORK, ASSIGNOR OF ONE-HALF
TO JOSEPH FOWLER, OF SAME PLACE.

DEVICE FOR FOLDING THE EDGES OF FABRICS.

SPECIFICATION forming part of Letters Patent No. 396,415, dated January 22, 1889.

Application filed October 5, 1888. Serial No. 287,277. (No model.)

To all whom it may concern:

Be it known that I, JOHN R. MORRISON, a citizen of Canada, residing at Glens Falls, in the county of Warren and State of New York, 5 have invented certain new and useful Improvements in Cloth-Folders, of which the following is a specification.

My invention relates to a folding device designed more particularly for use in the manufacture of cuffs, but equally applicable to other uses.

In the application filed by me, Serial No. 266,431, I have described a method of manufacturing cuffs in which I fold the edges of the facing over upon the interlining and then fold both fabrics together upon themselves; and the present invention is designed to accomplish this folding in a regular, smooth, and efficient manner.

20 In the drawings, Figure 1 is a top plan view of my improved folder; Fig. 2, a vertical longitudinal central sectional view of the same; Fig. 3, a transverse sectional view on the line $\alpha\alpha$, and Fig. 4 an end view.

25 A indicates a base-board or support, which will in practice be made of a plate of sheet metal, the said base being designed to support the two folding devices B C, which are arranged upon the plate or base directly in 30 line with each other, so as to cause a uniform folding of both edges of the fabric.

The folding devices B and C will be provided with lateral feet or wings D, slotted, as shown, to receive bolts or screws E, by 35 which they are adjustably secured to the plate or base-board A, as shown in Figs. 1 and 4.

40 The folding device B, by which the facing is folded upon the interlining, comprises three flat plates, F, G, and H, which are arranged parallel and secured rigidly in position relatively to each other, so as to form two passages or channels, I and J, which will be separated by the intermediate plate or partition, G, as shown in Figs. 2 and 3.

45 The lower plate, F, preferably, extends forward a short distance in advance of the top plate, H, while the plate or partition G terminates at a point about two inches (more or less) in rear of the front edges of plates F and 50 H, as shown in Fig. 2 and by dotted lines in

Fig. 1. At its front end the top plate, H, bends or curves downward slightly toward the bottom plate, so as to be on approximately the same line as the partition-plate G, as shown in Fig. 2, and the side edges of the lower plate, F, are bent into **U** form and folded over the edges of the free end of the plate H to form folding-lips N, as clearly shown in Fig. 1. It will be noticed that the upper channel or passage, J, is narrower than the lower channel, I, and that the interlining, when it emerges from the upper channel, is flat against the under face of the end of the plate H. The facing, as it comes from the channel I, is caught at its edges by the **U**-shaped lips N of the lower plate, F, and as such lips converge toward each other and extend over or overhang the projecting end of plate H they cause the edges of the facing to be laid over upon the edges of the interlining, 70 as is clearly illustrated in Fig. 1.

By curving or bending the end of the plate H downward close to plate F it causes the interlining to lie flat and close upon the facing.

As the fabric leaves the folder B, it enters 75 the folder C, which differs from the former in that it has but one channel or passage, K, formed by the plates L and M, the latter having the edges bent into lips O of **U** form and arranged to overhang the plate L, as shown 80 in Fig. 4, in a manner similar to the lips N. As the material passes through this folder C, its edges are caught in the folds of the **U**-shaped lips of the plate M, and thereby turned 85 upon itself, as clearly shown in Figs. 1 and 4.

The mouths of the folders B and C will advantageably be made flaring, as shown in Fig. 2, so as to more readily secure the easy entrance of the material.

Having thus described my invention, what I claim is—

1. In a device for folding the edges of one fabric upon the edges of another, the combination, with a folder, B, comprising the separated channels I, J, of different widths, one above the other, and the converging folding-lips N, of the folder C, provided with converging lips O, to receive the double fabric and fold it upon itself. 95

2. In a device for folding the edges of one fabric upon the edges of another, the combination of the plates F, G, and H, separated from one another to form channels I and J, of different widths, the plate G terminating short of the plates F and H, and the plate H being bent down in line with the plate G, and converging folding-lips N, formed upon the lower plate, F, and extending from the lower channel, I, upward toward each other and above and overhanging the plate H.
3. In a device for folding cloth, in combination with the folder B, having two channels, I and J, of different widths, separated by a partition, G; a plate, H, forming the top of the channel J and extending forward and downward in advance of and in line with the partition G, a plate, F, forming the bottom of the channel I and extending forward in advance of the partition G, and U-shaped fold-

ing-lips N, formed upon the plate F and converging toward each other above the upper plate, H.

4. In a device for folding the edges of one fabric upon the edges of another, the combination, with the body provided with two fabric-receiving channels, one above the other, and the lower channel of greater width than the upper, of converging folding-lips on each side of the body, arranged in line with the wider channel, to receive the fabric passing through the latter and to turn it over upon the edges of the fabric passing through the narrow channel.

In witness whereof I hereunto set my hand in the presence of two witnesses.

JOHN R. MORRISON.
